UNITED STATES PATENT OFFICE

PHILIP H. CHASE, OF BALA-CYNWYD, PENNSYLVANIA

RACK

Application filed June 4, 1928. Serial No. 282,577.

This invention relates to racks and with regard to certain more specific features to racks for insulators and like fixtures.

Among the several objects of the invention may be noted the provision of a locking base or piece for holding together a number of interchangeable rack units; the provision of a reinforcement for the base and legs of such interchangeable rack; the provision of a device of the class described which increases the strength of the legs of such racks to withstand both transverse and vertical loads; and in such a device the provision of reinforcement for the bottom leg of a lower unit so that it may withstand greater vertical loads. Other objects will be in part obvious and in part pointed out hereinafter.

The invention accordingly comprises the elements and combination of elements, features of construction, and arrangements of parts which will be exemplified in the structures hereinafter described, and the scope or application of which will be indicated in the following clauses.

In the accompanying drawings in which are illustrated various embodiments of the invention;

Fig. 1 is a side elevation showing one form of assembly of the rack;

Fig. 2 is a side elevation of Fig. 1;

Fig. 3 is a plan view of Fig. 1;

Figs. 4, 5 and 6 are views similar to Figs. 1, 2 and 3 showing a modified form of the device;

Figs. 7 and 8 are views similar to Figs. 4 and 5 illustrating the omission of certain fastening tongues and bolts; and

Figs. 9 and 10, taken together illustrate a juxtaposed relationship between certain rack units and a locking base.

Similar reference characters indicate corresponding parts throughout the several views of the drawings.

Referring now more particularly to Figs. 1, 2 and 3, there is illustrated a group of three U-shaped interchangeable rack units 1 which have been assembled by sliding the lower leg 3 of one rack unit along the upper leg 5 of the adjacently held rack unit so that the tongues 7 on said lower legs 3 engage

with holes 9 formed in the said upper legs 5.

Another way of holding the rack units 1 assembled is shown in Figs. 4 to 6, wherein bolt-and-nut combinations 11 are used.

In all the modifications herein described 55 a bolt, which is not shown in the drawings, passes through aligned holes 13 near the ends of the legs 3 and 5 and serves to lock the units together and also acts as a spindle to support spool type insulators, also not shown, 60 said insulators supporting line wires.

In the preferred embodiment of my invention, the legs 3 and 5 are provided with aligned notches 15 on either side, said notches being formed near the junctions of the legs 65 with backs 17 of said U-shaped units (Figs. 9 and 10).

A base or locking channel 18 with ears 20, formed to engage with the notches 15 is formed so as to be driven parallel with the aligned bases 17 of the rack 70 units and thereby locks together the rack units by connecting their backs in addition to the aforementioned locking between the legs of adjacent rack units. The notches 15

may be formed by cutting but preferably by 75 pinching without removal of material, in order to avoid decreasing the strength of the legs. There is thus afforded additional strength and stiffness to the assembled rack units. Such reinforcement as the tongues 80 and openings or nuts and bolts may be applied or omitted as conditions require, without loss of the advantages of flexibility, small number of parts and cheapness afforded by this invention. The base 18 is pro- 85

vided with holes 19 which line up with corresponding holes in the backs 17 of the rack units, as desired, irrespective of the length of the legs of the rack units.

It will be noted that in Figs. 1 to 3, the 90 backs and legs 17 of the rack units 1 have curved cross sections, while in Figs. 4 to 6 they have flat cross sections. It is to be understood that the channel 17 is made of 95 such depth so as to accommodate the particular type of rack units to which it is to be applied.

Figs. 7 and 8 illustrate the use of the locking channel 18 with a plurality of rack units 100

1 which are not fastened by bolting or tonguing together adjacent legs thereof. This method of construction may be employed where no assemblies of rack units in the field without the base 18 are required. Figs. 9 and 10 show 5 the relationship of parts prior to the application of the locking channel over the backs of the rack units. It is to be understood that the widths of the backs of the rack units are 10 slightly greater than the width of the channel in the locking channel piece 18, thereby affording a springing action when the channel piece is driven on so as to hold the pieces together.

15 In view of the above, it is believed that the various features of this invention will be clear without further elaboration, and it will be seen that with the apparatus herein described, the several objects of the invention 20 are achieved and other advantages results attained.

25 As many changes could be made in carrying out the above construction without departing from the scope of the invention, it is intended that matter contained in the above description or shown in the accompanying drawings shall be interpreted as illustrative and not in a limiting sense.

I claim:

30 A rack for insulators and the like comprising insulator supporting units having back portions and legs extending therefrom, notches in the legs near said back portions and a reenforcing channel surrounding at 35 least part of said back portions and engaging said notches.

In testimony whereof, I have signed my name to this specification this 31st day of May, 1928.

40 PHILIP H. CHASE.
